United States Patent Office

Des. 227,027

Patented May 29, 1973

227,027

FLOWER POT

Leon Tissot, 22 Rue du Mercier, Nantua, France

Filed Jan. 4, 1971, Ser. No. 103,938

Term of patent 14 years

Int. Cl. D11—02

U.S. Cl. D35—3

FIG-2

FIG-1

FIG. 1 is a side view of a flower pot with my new design; and

FIG. 2 is a top plan view of the flower pot.

The reverse side of the flower pot is identical to the side shown.

I claim:

The ornamental design for a flower pot, as shown and described.
